UNITED STATES PATENT OFFICE.

CLYDE K. BRANDENBURG, OF KLAMATH FALLS, OREGON.

TOOTH-CLEANER.

1,168,998.

Specification of Letters Patent.

Patented Jan. 18, 1916

Application filed October 13, 1914. Serial No. 866,490.

To all whom it may concern:

Be it known that I, CLYDE K. BRANDENBURG, a citizen of the United States, residing at Klamath Falls, in the county of 5 Klamath and State of Oregon, have invented certain new and useful Improvements in Tooth-Cleaners; and I do hereby declare the following to be a full, clear, and exact description of the invention, such as will enable others skilled in the art to which it 10 pertains to make and use the same.

This invention relates to tooth cleaners, and one of the principal objects of the invention is to provide a tooth cleaner in the 15 form of a brush or similar device connected to a flexible finger stall, so that the brush may be inserted in the mouth and carried by the finger, and said finger adapted to be flexed or bent to give the desired curvature 20 to the cleaner.

Another object of the invention is to provide a flexible tooth cleaner which can be inserted in the mouth by the finger, and moved to clean the teeth by an up and down 25 movement or by a circular movement, said cleaner being of simple construction and of inexpensive manufacture.

The foregoing and other objects may be attained by means of the construction illustrated in the accompanying drawing, in 30 which,

Figure 1 is a side elevation of one form of tooth cleaner made in accordance with this invention, Fig. 2 is a view of another 35 form of device connected to the finger of the user, and shown when the finger is bent to curve the cleaner. Fig. 3 is a sectional view of the same, and Fig. 4 is a rear end of the device shown in Fig. 1.

40 It will be understood that there are many forms of the device that need not be illustrated for a full understanding of the invention.

45 Referring to the drawing, the numeral 1 designates an elastic finger stall or cot, adapted to be engaged by the first joint of the finger, and as shown in Fig. 1, 2 indicating the middle joint of the finger. Cot 1 is connected to a suitable flexible base 3, 50 said base having bristles or other cleaning elements 4 connected thereto. As shown in

Fig. 1, a split ring 5 is connected to the base 3 at a suitable distance from the second joint of the finger to hold the cot or stall firmly in place. 55

As shown in Fig. 2, the cot or finger stall 1^a is extended beyond the joint 2 of the finger and is provided with a reinforcing band 5^a at its open end. The base or brush back 3^a is flexible and the cleaning element 60 4^a is shown as curved in this figure to fit the teeth.

From the foregoing it will be obvious that a cleaner for teeth made in accordance with this invention may be readily slipped onto 65 the finger of the user and suitable dentifrice be used and the brush or cleaning element may be moved up and down or vertically on the teeth as well as across the teeth, if desired. One of the advantages of this 70 construction resides in the fact that the finger is more readily controlled by the will of the operator than a stiff handled brush, and will find the places where it is desired to clean the teeth better than a handle. The 75 device can be manufactured at a very reasonable cost and should meet with favor by the public.

Various changes in the details of construction may be resorted to without departing from the spirit and scope of the invention as defined in the claim. 80

What is claimed is:

A tooth cleaner comprising a flexible strip, an elastic cot or finger stall mounted 85 upon one end of said strip, a split ring upon the opposite end of said strip, said flexible strip adapted to lie along the under side of the finger, two sets of bristles mounted upon the outer surface of said flexible strip and 90 being spaced apart to permit flexure of the strip between the sets of bristles and at a point approximately opposite the middle joint of the forefinger when in position for use. 95

In testimony whereof I affix my signature in presence of two witnesses.

CLYDE K. BRANDENBURG.

Witnesses:

IDA B. MOMYER,
A. R. CAMPBELL.
